UNITED STATES PATENT OFFICE.

WILLIAM A. PUNGS, OF DETROIT, MICHIGAN.

GARAGE.

Application filed February 12, 1923. Serial No. 618,573.

To all whom it may concern:

Be it known that I, WILLIAM A. PUNGS, a citizen of the United States of America, residing at Detroit, in the county of Wayne and State of Michigan, have invented certain new and useful Improvements in Garages, of which the following is a specification, reference being had therein to the accompanying drawings.

10 This invention relates to a garage and one of the objects of my invention is to provide a circular building portion in which automobiles and other vehicles may be compactly stored or temporarily placed in an expeditious and economical manner, the building portion including novel means whereby easy access can be had to any vehicle stored therein without any confusion in the movement of vehicles or danger to the same.

20 Another object of this invention is to furnish a garage with superposed sets of concentric movable car platforms served by an elevator movable axially of said car platforms.

25 A further object of this invention is to provide a garage of large capacity having circular storage compartments provided with movable car supporting platforms on a level with an elevator floor so that cars may be moved from an elevator on to either platform and shifted to a storage space without disturbing other cars that may be on said platforms.

I attain the above and other objects by a garage that may be partly underground and 35 partly above ground so that such building will occupy a minimum of space and yet have a large storage capacity. The novel arrangement of the storage compartments, car platforms and elevator will be herein-40 after described and then claimed, and reference will now be had to the drawing wherein—

Figure 1 is a vertical sectional view of the garage, partly broken away, showing an elevator in a lowered position centrally of the garage;

Fig. 2 is a horizontal sectional view of the same, and

Fig. 3 is a side elevation of a portion of 50 one of the movable car platforms of the garage.

The garage or that portion of the building used as a garage includes a plurality of concentrically arranged and vertically disposed 55 walls and as illustrating a small garage I

show an inner wall 1, an intermediate wall 2 and an outer wall 3, said wall supporting a suitable roof 4 and in the preferred form of construction extending below the street level 5 to a suitable foundation or basement 60 floor 6.

The circular wall 1 supports floors 7 having central openings 8 affording a well or shaft for a conventional form of elevator 9 that may be operated to raise or lower an automobile 10 or other vehicle relative to the floor 7, each of said floors being of sufficient area to permit of the automobile 10 readily moving about the floor and in emergency cases the floors 7 may be used for the storage 70 of automobiles.

Connecting the walls 1, 2 and 3 are circular floors 11 and on said floors are circular tracks 12 and racks 13. Movable on the tracks 12 are the trucks or wheels 14 of circular car platforms 15. The floors 11 are in a plane below the floors 7 so that the platforms 15 will be on a level with the floors 7, and the walls 1 and 2 have transversely alining doorways or openings 16 through which automobiles 80 may be shifted when removing a car from a garage or placing a car therein, and for this purpose the outer wall 3 has one or more doorways 17 at the street level 5.

As illustrating a conventional form of operating mechanism for the platforms 15, I provide the lower face of each platform with an electric motor 18 and a train of gears 19 driven from said motor with said train of gears including a pinion 20 meshing with 90 the rack 13 under the platform. Any suitable means may be employed for controlling the operation of the electric motors, such means being preferably located at the doorways 16 so that the owner of a car or an attendant of the building can shift a platform to permit of an automobile being removed therefrom or placed thereon, and in order to afford light in the storage compartments between the floors and walls of the building, 100 the walls 2 and 3 may be provided with windows 21.

Obviously the building will be fire proof and may have as large a storage capacity as the ground will permit. Furthermore, the 105 circular building may form part of another building or the street level floor be of such plan as to provide street store rooms or other compartments.

While in the drawing there is illustrated 110

a preferred embodiment of my invention, it is to be understood that the structural elements are susceptible to such variations and modifications as fall within the scope of the 5 appended claims.

What I claim is:—

1. A garage comprising concentric walls, rotatable car platforms between said walls, the innermost walls having doorways to permit of cars being moved from one platform to another, and means movable axially of the innermost wall to facilitate placing cars on said platforms. 10

2. A garage as called for in claim 1, wherein 15 in said car platforms are arranged in sets with the platforms of each set concentric of each other.

3. A garage including a circular building portion having superposed floors, circular 20 concentric rotatable car platforms on each floor, and an elevator in the center of the

circular building and movable through the building floors adapted to serve each floor.

4. A garage including concentric walls providing circular storage compartments 25 having floors, one of said walls having its floor in a plane above the other floors, an elevator movable through said floor, and movable car platforms on the other floors with said platforms in a horizontal plane with 30 said floor.

5. A garage as called for in claim 4, wherein said walls have doorways permitting of a car being driven from said elevator backward or forward through said doorways on to either platform. 35

6. A garage as called for in claim 4, wherein the floor area included by the innermost wall has a diameter approximately three times greater than the length of a car. 40

In testimony whereof I affix my signature.
WILLIAM A. PUNGS.
